ELECTRICAL RELAY

Clarence S. Snavely, Pittsburgh, Pa., assignor to
 The Union Switch & Signal Company, Swiss-
 vale, Pa., a corporation of Pennsylvania

Application December 23, 1939, Serial No. 310,713

5 Claims. (Cl. 200—104)

My invention relates to electrical relays, and particularly to electrical relays suitable for use in centralized traffic controlling systems for railroads, such, for example, as that disclosed in an application for Letters Patent of the United States, Serial No. 222,860, filed by myself and another on August 3, 1938, for Remote control systems.

One object of my invention is to provide an improved relay of the type described of simple, rugged and compact construction, which will operate without appreciable wear or change in operating characteristics over a long period of time and for a very large number of operations.

Another object of my invention is to provide a high speed relay of the type described which can be readily calibrated, and which will operate with predictable accuracy to permit it to function in timed sequence with a plurality of other similar relays operating on close marginal limits without special adjustment.

In accordance with my invention, the above objects are accomplished by providing the relay with two pairs of pole pieces, each pair of which cooperates with a separate armature. The pole pieces are formed on cores which are moulded into the top and bottom walls of an insulating frame, and the one pair of pole pieces is constantly magnetized by a permanent magnet while the other pair is at times energized by an electromagnet of which the associated cores form a part. The two armatures are secured to the opposite ends of a moulded contact operating member which is mounted for sliding movement in a manner to permit the two armatures to move toward and away from the associated pole pieces. The contact operating member is provided between the two armatures with a plurality of projections which form vertically spaced slots. Each of these slots receives the intermediate portion of a cooperating flexible contact finger which is moulded at one end into one of the side walls of the frame and which cooperates at its free end with a fixed contact finger also moulded into a side wall of the frame. The relay is calibrated to provide the desired operating characteristics by charging the permanent magnet and then discharging it to a value which will give the desired pick-up current, and also by varying the air gaps between the cores and the backstrap of the electromagnet. After the desired air gap is secured, the backstrap is fixed in place by means of a material which can be applied in a liquid, plastic or semiplastic state and which will subsequently harden.

Other objects and characteristic features of my invention will appear as the description proceeds.

The relay forming the subject matter of my present application is an improvement upon that disclosed and claimed in my prior Patent No. 2,178,289, granted on October 31, 1939, for electrical relays.

I shall describe one form of relay embodying my invention, and one method for securing certain parts of said relay together, and shall then point out the novel features thereof in claims.

In the accompanying drawings, Fig. 1 is a front elevational view showing one form of relay embodying my invention, the front plate of the relay being removed to better illustrate the construction of the operating parts of the relay. Fig. 2 is a vertical sectional view of the relay shown in Fig. 1 taken substantially on the line II—II of Fig. 1. Fig. 3 is a top plan view of the relay shown in Fig. 1. Fig. 4 is a sectional view of the relay shown in Fig. 1 taken substantially on the line IV—IV of Fig. 1. Figs. 5, 6 and 7 are back, side and top views, respectively, of the contact operating member 27 forming part of the relay shown in Fig. 1. Fig. 8 is a detail view of the member 32 forming part of the relay shown in Figs. 1 and 2. Figs. 9, 10 and 11 are diagrammatic views illustrating certain features of the relay embodying my invention. Figs. 12 and 13 are enlarged views showing the means employed for securing the backstrap 13 to the cores 11 and 11a of the electromagnet A of the relay shown in Fig. 1 together with a mould for applying this means.

Similar reference characters refer to similar parts in each of the several views.

Referring first to Figs. 1, 2 and 3, the relay in the form here shown comprises a suitable case consisting of a front cover plate 1 and a back cover plate 2 clamped by suitable means not shown against the opposite sides of a rectangular frame 7 of suitable insulating material, such for example as a phenol condensation product. This case encloses all of the operating parts of the relay, and in order to permit ready inspection of the operating parts without the necessity for removing the cover plates, the front cover plate is formed with a window 8 which is closed by a window glass 9.

Mounted on the top wall 7a of the frame 7 is an electromagnet A comprising a pair of coils 10 and 10a disposed on spaced parallel cores 11 and 11a, the lower ends of which extend downwardly through the top wall 7a and terminate on the underside thereof in enlarged pole pieces 12 and

12a. The electromagnet A also comprises a back-strap 13 which is secured to the upper ends of the cores 11 and 11a in a manner which I shall describe hereinafter. The coils 10 and 10a are connected in series between the inner ends of two coil connectors 14a and 14b which are moulded into the opposite side walls 7b and 7c of the frame 7, suitable recesses 15 being provided in the back cover plate 2 to provide paths for the coil leads to be brought into the relay case. 10 The cores 11 and 11a may be secured to the top wall 7a in any convenient manner, but as here shown they are moulded into the top wall.

The relay also comprises an auxiliary pair of spaced parallel cores 16 and 16a which are moulded into the bottom wall 7d of the frame 7 in axial alignment with the cores 10 and 10a of the electromagnet A, and which terminate at their upper ends in enlarged auxiliary pole pieces 17 and 17a. The lower ends of the cores 16 and 16a are also enlarged and are engaged by the opposite ends of a permanent magnet 18. The permanent magnet 18 is held against the enlarged ends of the cores 16 and 16a by means of a curved flexible strip 20 and a bottom plate 21, and in order to provide an efficient magnetic connection between the auxiliary cores and the permanent magnet, the engaging faces of the auxiliary cores and the permanent magnet are ground to lie in the same plane. The bottom plate 21 fits at its ends in transverse grooves 23 provided in depending legs 7e and 7f which form extensions of the side walls 7b and 7c of the frame 7, and at its sides in grooves 24 and 24a formed respectively in the front and back cover plates 1 and 2.

The pole pieces 12 and 12a cooperate with a main armature 25, while the auxiliary pole pieces 17 and 17a cooperate with an auxiliary armature 26. The two armatures 25 and 26 are moulded onto, or otherwise secured to, the opposite ends of a contact operating member 27 of suitable insulating material in such manner that the upper face of the armature 25 and the lower face of the armature 26 lie in parallel planes, and these armatures act to move the contact operating member vertically between a lower position in which the armature 26 engages a stop 28 moulded onto the bottom wall 7d of the frame 7 and an upper position in which the armature 25 engages the lower faces of the pole pieces 12 and 12a, according as the electromagnet A is de-energized or energized. The parallel faces of the two armatures are chromium plated to present smooth wearing surfaces to their respective engaging surfaces. Furthermore, the pole pieces with which the armatures cooperate are also chromium plated and polished, the chromium plating on the pole pieces 12 and 12a serving in conjunction with the chromium plating on the armature 25 to take the place of the usual core pins to prevent the armature 25 from sticking in its attracted position due to any residual magnetism which may be present in the cores of the electromagnet A when it is deenergized.

The contact operating member 27 is guided to move vertically by means of a vertical guide rod 30 which extends with some clearance through aligned opening 27a formed in vertically spaced lugs 27b provided on the rear side of the operating member 27. This guide rod is mounted at its upper end in an opening 31 provided in a transversely extending bar 32, and at its lower end in an opening 33 provided in the bottom

5 wall 7d of the frame 7. The bar 32 fits at its ends in recesses 34 formed in the side walls 7b and 7c of the frame 7 above the coil connectors 14a and 14b and is held in place in the recesses by means of the back cover plate 2. The lower end of the guide rod is held in place in the opening 33 by means of a mass 33a of material which can be applied in a liquid or molten state and which will subsequently harden. A preferred material for this purpose is 7 per cent antimony lead. To reduce friction and wear to a minimum the guide rod 30 is provided with a smooth polished surface, such for example as that obtainable by chromium plating.

15 The bar 32, in addition to serving as a positioning means for the upper end of the guide rod 27, is provided on the side adjacent to the armature 25 with laterally projecting pads 32a and 32b which cooperate with the side of the armature 25 to hold it and the contact operating member 27 in the desired angular position relative to the pole pieces and other parts of the relay. These pads are preferably chromium plated and polished to reduce friction to a minimum.

20 Formed on the rear side of the contact operating member 27 are a plurality of projections 35 which form slots 36. The slots 36 receive a plurality of vertically spaced superposed contact fingers 37 intermediate the ends of the fingers. The contact fingers 37 are moulded into the opposite side walls 7b and 7c of the frame 7 in such manner that alternate fingers are located in different legs and extend in opposite directions, and, 25 as here shown, each of the upper fingers cooperates with an associated fixed front contact finger 38 which is moulded into the side wall of the frame 7 opposite the side wall in which the finger is located, while the remaining fingers 30 each cooperate with a fixed back contact finger 39 which is likewise moulded in the side wall of the frame 7 opposite the side wall in which the associated flexible finger is moulded. To decrease contact resistance, the flexible contact fingers are each provided with contact buttons 40 of low resistance conducting material such as silver, which contact buttons cooperate with contact button 41, also of low resistance conducting material such as silver, provided on the associated fixed contact fingers. The contact fingers each extend through the associated side walls of the frame 7 and are provided with rounded outer ends which constitute plug portions to enable the relay to be readily plugged into suitable connectors such for example as those described in my copending application for Letters Patent of the United States, Serial No. 291,721, filed on August 24, 1939, for a Mounting means for relays. The outer ends of the two coil connectors 14a and 14b similarly extend outwardly through the associated side walls and are provided with rounded outer ends.

25 The operation of the relay as a whole is as follows: The parts are so proportioned that when contact operating member 27 is in its mid-stroke position, the flexible contact fingers 37 will be substantially unflexed and the contact buttons 40 on those flexible fingers which cooperate with the fixed front contact fingers 38 will be spaced the same distance from the buttons 41 on the front contact fingers as the contact buttons 40 on the flexible fingers which cooperate with the fixed back contact fingers 39 are spaced from the contact buttons 40 on these latter contact fingers. 30 The parts are further so proportioned that when

the electromagnet A is deenergized, the flux from the permanent magnet 18 traversing the auxiliary pole pieces 16 and 16a, together with the weight of the two armatures 25 and 26 and the weight of the contact operating member 27, will exert a sufficient biasing force on the contact operating member to move it downwardly to its lower position in which the armature 26 engages the stop 28, and that before the contact operating member reaches its lower position, the contact buttons 40 on each of the three lower flexible fingers will move into engagement with the contact buttons on the associated fixed contact fingers 39. It will be seen, therefore, that the movement of the contact operating member 27 to its lowermost position will cause the centers of those flexible fingers which cooperate with fixed back contact fingers to become forced downwardly at the point where they are engaged by the projections 35, thereby providing a limited amount of wiping action between the engaging contact buttons on the flexible contact fingers and the buttons on the fixed back contact fingers as the contact operating member moves to its lowermost position, and hence insuring that when the operating member occupies this lowermost position, the contact buttons on the flexible fingers will engage the contact buttons on the associated fixed back contact fingers with sufficient force to provide an effective low resistance contact. The downward movement of the contact operating member 27 will cause each of the flexible contact fingers which does not engage with a fixed back contact finger to continue to move downwardly at its free end until the armature 26 reaches its lower extreme position in which it engages the stop 28. It will be seen, therefore, that when the permanent magnet 18 is in place and the parts are properly adjusted, if the electromagnet A is then deenergized, the front contacts 37-38 of the relay will be open and the back contacts 37-39 will be closed.

When the electromagnet A becomes energized, the resultant flux which is set up by the current traversing the coils 10 and 10a will cause the armature 25 to move upwardly, in opposition to the bias of the permanent magnet and the weight of the two armatures and the associated contact operating member, and will thus move the contact operating member 27 to its upper extreme position in which it engages the pole pieces 12 and 12a. This upward movement will cause the contact buttons 40 on the flexible contact finger to move out of engagement with the button 41 on the back contact fingers 39, and into engagement with the buttons 41 on the front contact members, thereby opening the back contacts 37-39 and closing the front contacts 37-38. The parts are further so proportioned that the contact buttons 40 on the flexible contact fingers will move into engagement with the buttons 41 on the front contact fingers 38 before the armature 25 reaches its upper extreme position, and it will be seen, therefore, that the movement of the armature 25 to its upper extreme position will cause the flexible contact fingers 37 to become bowed upwardly intermediate their ends and will thus cause a limited amount of wiping action between the engaging contact buttons 40 and 41 as the armature 25 completes its upward movement, as well as insuring a good contact pressure to provide an efficient low resistance contact.

It will be noted from an inspection of Fig. 5 that alternate ones of the projections 35 on the contact operating member 27 are disposed on 75

opposite sides of the center line. This arrangement affords a number of advantages which can best be explained by reference to the views shown in Figs. 9, 10 and 11.

Referring to these views, Fig. 10 shows one of the front contacts 37-38 so adjusted that when the associated finger 37 is unstressed, the button 40 carried thereby will just touch the button 41 on the associated fixed front contact finger. With the finger adjusted in this manner, when the contact is opened by driving the operating member 27 downwardly to the position shown in Fig. 11, the finger 37 will free itself from the lower projection 35 as shown by the space 35a between the projection and the finger. Thus there is no tendency for the projection 35 to bind the finger when the contact is open. When the operating member 27 is driven upwardly from the position shown in Fig. 10, as is the case when the armature 25 is attracted, the contact member 37 then becomes compressed as shown in Fig. 9, and under these conditions the finger 37 frees itself from the upper projection 35. Thus there is no tendency to bind when the contact is compressed. Since there is no tendency for the contact finger to bind between the projections 35, it is unnecessary to accurately control the thickness of the projections or the distance between them. Furthermore, maladjustment of the contacts will not so adversely affect the operating characteristics of the relay as would otherwise be the case. Consider again Fig. 9. The bend in the contact finger 37 is exaggerated to show the non-binding advantage. Actually the spacing between the upper projection 35 and the finger is relatively small. Assume that the fixed front contact finger 38 is not adjusted as intended, but is bent upwardly from the position shown. When the contact button on the finger 37 is driven upwardly by the lower projection 35, it will not strike the button on the fixed front contact finger 38 at the point shown, since this latter finger is bent out of position. The finger 37 will, however, be bent as may be seen since the upper projection 35 prevents free counterclockwise rotation of the finger 37. The force necessary from the armature 25 of the relay to push the drive element 27 from one position to the other is only slightly less than if the fixed front contact finger has been correctly adjusted. A fixed front contact finger is shown in the diagram, but the same reasoning applies to a fixed back contact finger. The relay therefore has more stable characteristics when maladjustments occur than other relays of its type.

Refer again to Fig. 10. Assume that the contact button 40 on the movable contact finger 37 sticks to the contact button 41 on the fixed contact finger 38 due to frost or some other reason. When the contact operating member 27 is pulled downwardly by means of the permanent magnet, the upper projection 35 will force the contact finger 37 downwardly and will actually force the contact buttons 40 and 41 apart.

In assembling a relay constructed in accordance with my invention the contact alignment of the contact fingers with respect to the frame 7 is first checked in a suitable tool provided especially for that purpose. The contact operating member 27 is then placed inside the frame 7 with the slots 36 facing toward the rear, and receiving the flexible contact fingers 37. The bar 32 is next placed with its ends in the notches 34 in the frame 7 and with the pads 32a and 32b facing the armature 25. The guide rod 30 is then inserted from the bottom of the relay through

the opening 33 in the bottom wall 7d and through the two holes 27a in the lugs 27b of the contact operating member 27 into the hole 31 in the bar 32. The relay is then turned upside down and a magnetic force is applied to the cores 11 and 11a to hold the armature 25 against the pole pieces 12 and 12a. The securing means 33a is next applied, thereby insuring that the contact operating member 37 will be secured in place in the proper position with respect to the pole pieces. While the magnetic force is still applied to the cores, spacers of a definite thickness are inserted between the armature 25 and the pole pieces 12 and 12a, and the contact buttons on the front contact fingers 38 are then adjusted to just touch the contact buttons on the flexible contact fingers 37. The coils are then placed on the cores of the relay, and the backstrap 13 is placed on top of the cores 11 and 11a. The permanent magnet 18 is next adjusted as to strength by charging it fully and then discharging it to a value which will give the relay the correct pick-up value. Finally, the release time is adjusted in a manner which I shall describe presently, after which the relay is recalibrated, the front, back and bottom covers are assembled, and the relay is sealed.

As was pointed out hereinbefore, a relay embodying my invention is intended for use in centralized traffic controlling systems for railroads wherein large numbers of quickly replaceable relays are employed, and in systems of this type when the relays are used for timing purposes it is essential that relays performing like functions should have like release times to eliminate the necessity for providing excess operating margin. If the parts from which the relays are constructed are very accurately controlled, both with regard to dimensions and quality of material, the relays can be made near enough alike to require no adjustment. However, when relays are built in large quantities on a production basis, variables are liable to creep into both the dimensions and the quality of the material and the presence of these variables makes it desirable to provide some convenient means for compensating for the variations between relays. There are a variety of methods to obtain the necessary compensation, but due to the necessary qualities the method must have, particularly when applied to a centralized traffic control system, for example, there are very few methods which are entirely satisfactory. For example, temperature, vibration, humidity, time or use must not alter the adjustment once it has been made. The adjustment must not be too sensitive, so that it can be easily made. The parts must not be too complicated, particularly when silicon steel is used for the magnetic circuit, since silicon steel is difficult to work into shape. Above all, the adjustment must be tamper proof. That is, it must not be altered except by an authorized person.

In my improved relay I prefer to accomplish the necessary adjustment by varying the position of the backstrap 13 relative to the cores 11 and 11a of the electromagnet A, thereby varying the length of the air gaps between these members. The resulting variation in the reluctance of the magnetic circuit supplied with flux by the coils 10 and 10a provides a means whereby the release time or the shunt point of the relay may be varied minutely to accurately obtain a specific value. As shown in the drawings, the backstrap 13 is fastened to the upper ends of the cores 11 and

11a in a preadjusted position to provide the proper release time or shunt point of the relay by means of two masses 45 and 46 of a material which can be applied in a liquid, molten or plastic condition and which will subsequently harden. A number of different materials may be used for the securing means, but I prefer to use 7 per cent antimony lead because it pours very nicely when sufficiently hot, and retains its dimensions while cooling. In applying this securing material, I use a mould 47 or any other device capable of holding the material in place long enough to permit it to set. This mould is placed over the cores 11 and 11a on top of the coils 10 and 10a, and is secured in place by means of spring clips 48. The backstrap 13 is placed above the cores and held there temporarily by any suitable means such for example as a jig. The relay is then checked for release current or release time, depending upon which of these characteristics it is desired to accurately control. If the air gaps between the backstrap 13 and the cores are not such as to give the desired characteristics, these gaps are altered to provide the desired characteristics. There are several ways whereby the desired air gaps may be obtained. One way to accomplish this result is to leave the ends of the cores and the surfaces of the backstrap 13 opposite the cores unplated and insert non-magnetic spacers between the backstrap and the cores. Another way to accomplish this result is to plate the cores or the backstrap or both and gradually remove a part of the plating as by a fine abrasive until the desired air gaps are obtained. A third way of accomplishing this result is to hold the backstrap away from the cores by spring means and to gradually compress this spring means to force the backstrap toward the cores, by means of screws provided in the jig which holds the backstrap in place, until the proper air gaps are obtained. After the desired air gaps have been obtained, the securing means 45 and 46 are inserted into the moulds and allowed to harden. The mould is then removed by pulling off the two clips 48 and pulling the two halves apart.

In case it is desired to subsequently alter the adjustment once it has been made, it is only necessary to pry the backstrap off and remove the securing means 45 and 46 from the cores and the backstrap and then repeat the process just described.

To facilitate holding the backstrap 13 in place by means of the material 45 and 46, annular grooves 49 may be provided in the upper ends of the cores 11 and 11a and pins 50 may be inserted in the backstrap in positions to be engaged by the fastening means.

One advantage of securing the backstrap 13 to the cores in the manner just described is that the necessary adjustment may be made as accurately as measuring instruments will measure it.

Another advantage of securing the backstrap to the cores in the manner just described is that the adjustment is simple enough to be made by anyone capable of reading an ordinary measuring instrument.

A third advantage of securing the backstrap to the cores in the manner just described is that the adjustment is sensitive enough to be obtained easily, but is not so sensitive as to be unstable. Furthermore, after the adjustment has once been made, it is permanently fixed until changes in operating conditions require that the adjustment be altered when it can readily be changed.

A further advantage of securing the backstrap to the cores in the manner described is that this means is economical since the parts are simple and the adjustment is easily made.

A final advantage of securing the backstrap to the cores in the manner described is that the adjustment is fool proof since it is necessary to have the proper tools to remake it.

One advantage of the relay as a whole when constructed in the manner described is that since the permanent magnet circuit is separated from the electromagnet circuit, it is easy to design the magnetic circuit to produce the desired results. Furthermore, the results obtained from the relay are the same regardless of which direction the current flows through the operating coils 10 and 10a. This decreases the cost of manufacture as well as of maintenance.

The fact that the cores and permanent magnet pole pieces are all moulded into the same piece as the contacts permits the elimination of two moulded parts and therefore greatly decreases cost. This fact also makes the contact frame sturdier and therefore less liable to warp or break. The fact that the contact frame is sturdier permits the Bakelite walls to be much thinner, which in turn eliminates a serious manufacturing objection. For example, the flexible contact fingers 37 are inserted into slots in the steel mould during the moulding process, the portions of the springs shown inside the Bakelite being in the cavity formed by the mould, while the portions of the springs outside of the Bakelite being fixed by the walls of the mould. While the Bakelite is semifluid and the plunger of the mould is being closed, the plastic flows into the cavity of the mould in either direction past the contact fingers depending on the shape of the piece and how evenly the loading is done. This flow of semi-fluid Bakelite past a contact finger 40 sets up a condition on the finger similar to the conditions on a uniformly loaded beam fixed at both ends. From the theory of beams the deflection of a beam at the center, in this case the deflection of the finger at the center of the Bakelite wall, varies directly as the fourth power of the length and inversely as the cube of the thickness. For operating reasons it is not desirable to increase the thickness of the fingers. The addition of reinforcement is not desirable due to the added complexity. If, however, the thickness of the wall can be decreased from say $\frac{1}{2}$ to $\frac{1}{4}$ of an inch the deflection of the finger at the center is less by the ratio of 40 to 140. This fact alone decreases the amount of labor necessary to assemble and adjust the relay as well as making it a more reliable instrument.

Although I have herein shown and described only one form of electrical relay embodying my invention, it is understood that various changes and modifications may be made therein within the scope of the appended claims without departing from the spirit and scope of my invention.

Having thus described my invention, what I claim is:

1. An electrical relay comprising a plurality of flexible contact fingers rigidly supported at one end and cooperating at their free ends with fixed contact fingers, a contact operating member mounted for straight line movement between two extreme positions and provided with a plurality of projections forming slots through which the entire width of said flexible fingers extend intermediate their ends, the two projections which form each slot being disposed on opposite sides 70 75

of the center line of said member and being so spaced that when said member is in its mid stroke position they will just touch the opposite sides of the associated finger, whereby said fingers are positively moved between two positions in response to movement of said member between its two positions but that binding of said fingers in said slots is prevented, and electromagnetic means for actuating said contact operating member between its two extreme positions.

2. An electrical relay comprising a rectangular frame of moulded insulating material provided in its opposite side walls adjacent one end thereof with slots, a plurality of flexible contact fingers moulded into the side walls of said frame in parallel spaced relation, fixed contact fingers moulded into the side walls of said frame and cooperating with said flexible fingers at their free ends, a bar mounted at its ends in said slots and provided with a hole, a guide rod having one end disposed in said hole and the other end secured in a hole in the opposite end wall of said frame, a contact operating member provided with spaced lugs provided with aligned holes which receive said guide rod with clearance for limiting the movement of said contact operating members to longitudinal sliding movement, means on said contact operating member for engaging said flexible fingers intermediate their ends, and electromagnetic means for moving said contact operating members between two extreme positions to operate said flexible contact fingers.

3. An electrical relay comprising a rectangular frame of moulded insulating material provided in its opposite side walls adjacent one end thereof with slots, a plurality of flexible contact fingers moulded into the side walls of said frame in parallel spaced relation, fixed contact fingers moulded into the side walls of said frame and cooperating with said flexible fingers at their free ends, a bar mounted at its ends in said slots and provided with a hole, a guide rod having one end disposed in said hole and the other end secured in a hole in the opposite end wall of said frame, a contact operating member provided with spaced lugs provided with aligned holes which receive said guide rod with clearance for limiting the movement of said contact operating member to longitudinal sliding movement, means on said contact operating member for engaging said flexible fingers intermediate their ends, an armature secured at one end to said contact operating member and cooperating at its sides with pads provided on said bar to prevent said contact operating member from turning, and electromagnetic means including said armature for moving said contact operating member between two extreme positions to operate said contacts.

4. An electrical relay comprising a rectangular frame provided in its opposite side walls adjacent one end thereof with slots and having a first pair of cores moulded into one end wall and a second pair of cores moulded into the other end wall, said two pairs of cores being provided at their inner ends with pole faces which lie in parallel planes, windings on one pair of cores for at times magnetizing them, a permanent magnet engaging the other pair of cores for constantly magnetizing them, flexible contact fingers moulded into the side walls of said frame in parallel spaced relation and cooperating with fixed contact fingers moulded into the side walls of said frame, a bar mounted at its ends in said slots and provided with a hole, a guide rod having one end disposed in said hole and the other end secured

in a hole in the opposite end wall of said frame, a contact operating member provided with spaced lugs provided with aligned holes which receive said guide rod with clearance for limiting the movement of said contact operating member to longitudinal sliding movement, means on said contact operating member for engaging said fingers intermediate their ends, and two armatures one secured to each end of said contact operating member for cooperation with the pole faces of said two pairs of cores respectively, said bar being provided with pads which cooperate with the one side of one of said armatures to prevent said contact operating member from turning.

5. An electrical relay comprising a rectangular frame of moulded insulating material, a plurality of flexible contact fingers moulded into the side walls of said frame in parallel spaced relation and cooperating with fixed contact fingers moulded into the side walls of said frame, each 10 fixed contact finger being moulded into the side

wall opposite to that in which the flexible finger with which it cooperates is moulded, a contact operating member mounted in said frame for straight line movement between two extreme positions and provided with a plurality of projections forming slots through which the entire widths of said flexible fingers extend intermediate their ends, alternate ones of said projections being disposed on opposite sides of the center line of said member and being spaced apart such a distance that when said member is in its mid stroke position the two projections on opposite sides of each flexible finger will just touch the finger, whereby the flexible fingers are positively moved in both directions by said member to operate the relay contacts but that binding of the fingers within the slots formed by said projections is prevented, and electromagnetic means for actuating said contact operating member between its two extreme positions.

CLARENCE S. SNAVELY.
